United States Patent

Des. 235,376
Patented June 10, 1975

235,376

VERTICALLY ADJUSTABLE SEWING MACHINE CABINET

Robert S. Peets, Watchung, N.J., assignor to
The Singer Company

Filed No. 12, 1973, Ser. No. 415,283

Term of patent 14 years

Int. Cl. D15—06

U.S. CL. D70—1

Fig. 1

Fig. 2

Fig. 3

Fig. 4

FIG. 1 is a front, top and left side perspective view of a vertically adjustable sewing machine cabinet showing my new design with the legs in extended position;

FIG. 2 is a rear, top and right side perspective view thereof;

FIG. 3 is a front, top and left side perspective view with the legs in retracted position; and

FIG. 4 is a rear, top and right side perspective view thereof.

I claim:

The ornamental design for a vertically adjustable sewing machine cabinet, as shown and described.
